S. Leonard,

Horse Power.

Patented Sep. 23, 1834.

Silvanus Leonard of Hampden, Maine
Letters Patent

The Schedule referred to in these Letters Patent and making part of the same, containing a description in the words of the said Silvanus Leonard himself, of his improvement in machinery usually denominated a Horse Power

To all persons to whom these presents shall come, Silvanus Leonard of Hampden, in the County of Penobscot, and State of Maine, House Carpenter, sends Greeting. Be it known that I, the said Silvanus Leonard, have invented, made, and applied to use, a new and useful invention in machinery usually denominated as "Horse Power". The disposition, arrangement and uses of the several parts, I have fully described and set forth in the following words, and annexed drawings, which taken in connection, form my specification.

A. Figs 1 & 2 represent the frame made of timber or iron or other suitable material, shaped as seen in the drawings, or in other respects, suitably constructed to answer the intended purpose of supporting the machinery. B. is a horizontal bevelled wheel on the upright main shaft C. The lower end or foot of the main shaft C, turns, and is supported in a bearing or step in the usual manner, while to the top or upper end, is connected a long lever D. having at its opposite extremity a bow or other suitable fixture for attaching a horse to the same, the horse being the driving power. The bevelled wheel B acts on a bevelled pinion E. on a horizontal shaft F, having on its other end a cogged wheel G. whose teeth engage into the teeth of a small cogged pinion H. on a horizontal shaft I. and by this action on the same turn around the shaft I. This shaft I. has fixed on its other extremity or in any other convenient place, a large pulley or drum K. around which an end of belt L is passed. From the pulley

K. The belt is continuous and in the guide pulleys M, N placed on each side of the horse track O, and so situated that the belt shall pass under the horse track as seen in the drawings of figs 1 & 2. From under this last pulley, the belt is carried over and around the pulley or drum P, affixed to the machine. It is proposed to have or act on. I have applied this machinery to be moved by a horse, to a Threshing Machine, but I do not mean to confine it exclusively to that purpose, but to operate and drive my machinery to which it may conveniently attach and used to advantage.

I claim in the above the peculiar arrangement or combination of the several parts, for the purpose, above mentioned, and separately and singly as a part of this combination, I claim guiding the belt with passage from the pulley K to the pulley P, in a direction under the horse path or platform by small pulleys M & N, as seen and represented in the drawings. For testimony that the above is a true specification of my said invention I have hereunto set my hand this twenty fifth day of August in the year of our Lord Eighteen Hundred and thirty four
